DESIGN FOR A BIRD BATH

Charles E. Gautschi, Port Washington, N. Y.

Application February 5, 1940, Serial No. 90,062

Term of patent 14 years

To all whom it may concern:

Be it known that I, Charles E. Gautschi, a citizen of the United States, residing at Port Washington in the county of Nassau and the State of New York, have invented a new, original, and ornamental Design for Bird Baths, of which the following is a specification, reference being had to the accompanying drawing, forming a part thereof.

Fig. 1 is a front perspective view of a bird bath showing my new design;

Fig. 2 is a side perspective view thereof; and

Fig. 3 is a rear perspective view, showing my new design.

I claim:

The ornamental design for a bird bath, as shown.

CHARLES E. GAUTSCHI.
